SPILLWAY INSTALLATION FOR DAMS

Pierre F. Danel, Grenoble, France, assignor to
 Ateliers Neyret-Beylier & Piccard-Pictet, Grenoble, France, a corporation of the French Republic

Application July 5, 1947, Serial No. 759,187
 In France July 5, 1946

5 Claims. (Cl. 61—18)

1

The present invention relates to improvements in spillway installations for controlling the discharge of flood waters over dam or weir structures.

In the prior practice of discharging flood waters through spillways formed at or adjacent the top of a dam structure so that the water is permitted to flow down over the downstream side of the face of the dam, it has been customary to mount sluice gates of the sector type above the spillway for rotation about a point of support toward and away from the sill portion of the spillway at or adjacent the highest point thereof.

Because of the necessity for arranging the point of support of the sluice gate and its operating mechanism outside the path of flow of the discharging stream, according to one prior method shown in Fig. 1, the gate has been mounted for movement about a pivot located directly above the spillway. As shown, when the gate is in closed position its face is inclined inwardly at a substantial angle. Consequently, it must have a substantially larger expanse than the cross section of the overflowing stream even when the latter is at its maximum flow.

In order to reduce the size of the gate and also lessen the power demand for operating it, it has been proposed to associate the gate with a separate structure supported above the dam structure, such as shown in Fig. 2, which serves as a stationary barrier and cooperates with the pivoted gate on the upper side of the spillway. While the arrangement of Fig. 2 brings about some reduction in the cost of the gate and its operation, both this arrangement and that of Fig. 1 suffer from the drawback that even reasonably satisfactory flow characteristics are not assured unless the spillway sill is extended inwardly from the upstream face of the dam so as to make it possible to give the sill a surface contour favorable to smooth and non-turbulent flow of the nappe over it and down the outer face of the dam. The extension of the lip of the spillway inwardly, as shown, involves a considerable item of added expense when constructing large dams for hydroelectric and flood control purposes to which the invention is particularly adapted.

Even when the spillway sill contour is modified by providing an inwardly extending lip portion as shown in Figs. 1 and 2, there still remains a tendency for the nappe not to adhere continuously and smoothly to the outer wall surface of the dam. When the gate is not operated until a substantial head of water is built up, this tendency will be increased and the water may spurt

2

out away from the downstream face of the dam instead of flowing downwardly in a smooth stream thereover. Such spouting and subsequent falling back of the water upon the inclined downstream face of the dam leads to erosion and ultimate serious deterioration of the dam structure.

The present invention has for an object to bring about an improved streamlined flow of the nappe over the spillway while at the same time reducing the size of the sluice gates for a given volume of discharge.

It is a further object of the invention to realize the above advantages without resort to the expensive overhanging lip construction employed in the prior art installation.

These and other objects and advantages are achieved according to my invention by providing a spillway in the form of an outwardly and downwardly curved passage, the upper and lower walls 20 of which converge for a distance from the entrance end and eventually become substantially parallel. The form of the passage may also be compared to that of a curved tuyère when viewed in cross section. The lower wall of the passage 25 determines the water overflow level for the dam and includes a streamlined sill which may be of greater or lesser curvature depending on the volume of water that is to be permitted to become impounded above the overflow level and upon the inclination of the outer downstream wall surface of the dam, and is characterized by a smoothly curved outwardly and downwardly inclined surface which merges into the outer wall of the dam. The upper wall of the passage 30 may be formed by an upward extension of the massive structure of the dam or by any suitable structure supported on the dam structure in spaced relation to the curved sill. This upper wall is likewise smoothly curved outwardly and downwardly and extends downwardly at least substantially to the horizontal plane intersected by the crest portion of the sill and may continue somewhat below that plane. The curvature and spacing of this upper wall from the lower wall 35 are so determined as to insure that the water in traveling through the passage shall have become changed in its direction of flow so that as it exits from the passage it is traveling downwardly in a direction parallel to and in direct contact on the one side with the downstream wall surface of the dam that functions as a continuation of the spillway. A sluice gate is placed at or adjacent the discharge end of the downwardly directed passage.

Because of the known characteristic of a nappe

to contract as it descends from the crest of a weir or spillway, the cross section of the passage at the discharge end thereof may be very much reduced and, as a consequence, the sluice gate may be correspondingly reduced in size.

The invention will be more particularly set forth and described with reference to the accompanying drawings, in which:

Figs. 1 and 2 are vertical sections of the spillway constructions of the prior art that have been mentioned above;

Fig. 3 is a vertical section of a dam structure to which the present invention has been applied;

Fig. 4 is a vertical section of a dam structure embodying a modified form of the invention; 15 and

Fig. 5 is a vertical section of a dam structure to which still another modification of the invention has been applied.

As shown in Fig. 3, the invention is applied to a dam 10 by providing at the crest of the main supporting wall of the dam a rounded sill and associating therewith a streamlined wall section 12 which extends on its inner side upwardly to a point above the maximum water level 13 and is curved outwardly and downwardly from a point 15 to the point 16 where it assumes a direction substantially parallel with the downstream face 17 of the dam. The wall section 12 is supported in part directly on the main supporting wall of the dam, partly by means of the spaced piers 18 and partly by the supporting buttresses 19 which are shown as disposed in alinement with the piers 18 and as carried by and merging into the downstream side wall of the dam. As further shown in Fig. 3, the superimposed structure may also include an outer wall 20 and a wall 21 connecting the walls 12 and 20 adjacent their upper ends. The wall 21 may be made sufficiently massive and with supports adequate to serve as a roadway along the top of the dam structure. The sluice gate 22 is pivotally supported at 23 and is operated by a motor 24 and a winding drum 25 housed within the superimposed structure and connected to the gate by means of a cable 26 attached to the gate at 27 and running over a pulley 28.

In the modification of Fig. 4, the superimposed structure is shown as a solid massive, but in respect of the contours of the opposed side walls of the superimposed structure and the sill the arrangement is similar to that of Fig. 3. In this case, however, the sluice gate is provided with operating motors 24' which are carried within the gate itself and these are connected to jack rods 29 secured to and bearing against the side wall of the dam or preferably against pillars thereof extending upwardly between the adjacent spillway passages.

Sluice gates of the hollow sector type are preferably employed because they have the advantage over other types that they do not require the provision of guiding slots or grooves which give rise to more or less leakage that under some circumstances may be undesirable. However, other types of gates may be used in case loss of head due to leakage is not important.

According to the modification of Fig. 5, the superimposed structure may consist of a metal hood 30 supported upon the dam in any suitable way, not shown. As shown, the hood extends considerably above the maximum water level for a portion of its extent and thus cooperates with the rounded sill 11' of the dam to form a passage that is quite similar to that of a siphon, with this difference, however, that there is no

possibility of stoppage of flow due to loss of priming as is the case with a siphon. A construction such as shown in Fig. 5 has the advantage that it does not require any cutting away of the dam structure.

It will be understood that the superimposed structure plays an important role in directing the nappe downwardly and causing it to flow upon and along the downstream face of the dam. In fact, in the embodiments of the invention shown in the drawings, the upper wall of the spillway passage is so shaped as positively to depress the overflowing sheet of water to some extent and when the overlying wall is continued in this manner to a point at least approximately opposite the point of merger of the sill with the outer side wall of the dam, and is so shaped in the terminal portion thereof as to direct the nappe in a direction substantially parallel to the downstream face of the dam, it serves to suppress entirely any tendency of the nappe to move away from the dam surface.

Although the nappe does not attain its maximum contraction until it reaches the foot of the dam, it has been found that the tendency to further contraction becomes feeble beyond the point of discharge from the spillway passage when it is constructed in the manner above described. Therefore, by placing the sluice gate at or below the point where the spillway sill has merged with the downstream face of the dam, the practical maximum reduction in the size of the sluice gate for a given volume of discharge is insured. Since the size of the sluice gate and the length of the upper wall of the spillway passage are factors which enter into the cost of the dam, it will be understood that from the cost standpoint the optimum position for the sluice gate will be at or around, and preferably slightly below, the intersection or point of merger of the sill with the downstream side wall of the dam, assuming, of course, that the upper wall of the spillway passage opposite and immediately above this point has been so shaped as to insure the desired orientation of the descending nappe slightly toward or at least parallel with the downstream side wall.

Economies in construction cost and in operating expense are achieved from the above arrangement even though the sluice gate is subjected to a somewhat higher head during periods when it is completely or partly closed.

The advantages of smooth flow and continuous adherence of the nappe to the downstream side wall of the dam with suppression of tendencies to erosion are realized even under conditions of operation when the sluice gate is only partially open, for example, as in Fig. 4. The invention has the further advantage that the desired smooth flow and adherence of the nappe may be brought about even under conditions of low head and when the streamlining of the spillway sill is not adapted by itself to insure that the water in flowing thereover in the form of a thin sheet will pass onto and along the downstream facing of the dam as a continuous adhering sheet. In such conditions, the desired discharge of the water onto and along the facing of the dam may be assured by closing the sluice gate to the desired extent.

The structural arrangements of the present invention have the further advantage, as contrasted with the prior constructions employing sluice gates operating at the upstream level, that bodies floating on the surface of the water are

intercepted by the solid structure in a zone where the flow velocities are low, and, if desired, a small auxiliary outlet may be provided toward which the bodies are directed along the face of the solid structure.

When the superimposed structure is built into the dam, as, for example, in the forms of Figs. 3 and 4, it may be made to play the role of supporting beams of the buttress type imparting structural strength to the dam.

It will be understood that the invention may be applied in various ways other than those illustrated and that various changes may be made in the details of the construction and in the arrangements of the related elements without departing from the invention which is not to be deemed as limited otherwise than as indicated by the language of the appended claims.

I claim:

1. In a spillway installation for dams wherein the downstream face of the dam is inclined outwardly and downwardly to provide an extended spillway surface freely open to the atmosphere at least along the lower portions thereof, the improvement which includes an outwardly and downwardly inclined sill which merges in the form of a smooth curve into the downstream face of the dam, means positioned above and in spaced relation to the sill for directing water overflowing said sill downwardly in a direction substantially parallel to the downstream face of said dam and in contact therewith, and a sluice gate movable toward and away from the downstream face of said dam across the orifice defined between said means and the downstream face of said dam.

2. In a spillway installation for dams wherein the downstream face of the dam is inclined outwardly and downwardly to provide an extended spillway surface freely open to the atmosphere at least along the lower portions thereof, the improvement which includes an outwardly and downwardly inclined sill which merges in the form of a smooth curve into the downstream face of the dam, means positioned above and in spaced relation to said sill and defining therebetween an outwardly and downwardly extending streamlined passage for water overflowing said sill, said passage in the lower portion thereof being substantially parallel and in line with the downstream face of said dam and being of substantially reduced cross-section as compared with the portion adjacent the top of said sill, and a sluice gate movable toward and away from the downstream face of said dam across said passage in the portion thereof of reduced cross-section.

3. In a spillway installation for dams wherein the downstream face of the dam is inclined outwardly and downwardly to provide an extended spillway surface, the improvement which includes a spillway defined by an outwardly and downwardly inclined sill which merges in the form of a smooth curve into the downstream face of the dam, a barrier disposed above and in spaced relation to said sill and defining between said sill and said barrier an outwardly

and downwardly extending passage through which flood waters are guided in a direction paralleling and in contact with the downstream face of said dam, said barrier including a wall portion extending in spaced relation to the outer wall of said sill to a point at least opposite the point of merger of said sill with the downstream face of said dam but terminating a substantial distance above the foot of said dam, and said wall portion in the lower part thereof also extending in a plane substantially parallel to the plane of the downstream face of said dam, and a sluice gate mounted adjacent the lower end of said passage for pivotal movement toward and away from the outer wall of said dam for controlling the flow of water past said spillway.

4. In a spillway installation for dams wherein the downstream face of the dam is inclined outwardly and downwardly to provide an extended spillway surface, the improvement which includes an extension of the dam structure to a height above the maximum water level under flood conditions, the provision in the dam face beneath the crest of the dam of a smoothly curved spillway passage extending outwardly and downwardly to a point below the sill portion of said spillway but terminating a substantial distance above the foot of said dam, said passage being defined on the upper, outer side thereof by a smoothly curved wall portion which gradually converges toward the inner wall portion until it assumes a position approximately parallel with the inner wall at the level of the sill and then continues for a short distance downwardly in parallel relation to the downstream face of the dam, and a sluice gate of the sector type mounted adjacent the lower end of said passage on a pivot supported outside the line of flow through said passage for movement toward and away from the downstream face of the dam for controlling the flow of water past said spillway and causing the water when it is discharged in the form of a restricted flow to travel downwardly along the downstream face of said dam.

5. The improvement in spillway installations according to claim 1, wherein the operating mechanism for the gate includes jack rods bearing against the downstream face of the dam operated by motive mechanism housed within the sluice gate.
